Application June 19, 1940, Serial No. 341,385

10 Claims. (CL 62—115)

This invention relates to refrigeration and particularly to maintenance of oil in the crank cases of a plurality of compressors connected between the same suction or discharge lines and controlled in such a way that they are selectively cut out of operation, so that all or some less number operate, depending on the load.

The problem arises particularly with "Freon," with which lubricating oil is freely miscible in all proportions so that gravity separation is impracticable and tendencies to pump oil with the refrigerant are accentuated.

Where a large number of compressors are used (and installations using eight are now in commercial use to secure extreme flexibility and freedom from severe vibration), it is very difficult to assure adequate supply of oil to all compressor crank cases. Connection of the crank cases by oil and gas pressure equalizing lines will not suffice because pressure differences which inevitably exist between idle and active compressors, particularly compressors which have just started up, cause the idle compressors to rob the active ones of oil.

The system of the Zercher Patent 2,076,332 will operate but requires periodic shut-downs to permit oil equalization to occur and this is not practicable with large installations which remain in almost continuous operation, at least at part capacity.

All compressors pump out some oil with refrigerant. With certain types of evaporators the oil tends to accumulate in the evaporator. Various schemes, some of which use stills, have been devised to separate this oil from refrigerant and thus recover the oil. Other types of evaporators discharge the oil to the suction line, from which it may be drained to a sump and again used.

The problem in multiple compressor installations, regardless of the particular system of oil recovery, is to assure delivery of the recovered oil in proper quantity to all crank cases, of both active and idle compressors, maintain an adequate reserve of oil, and prevent serious flooding of any crank case with oil.

The present invention offers several solutions of this problem, some of which are suited particularly to compressors having force feed lubrication.

In the embodiment chosen for illustration the oil is recovered from a mixture of oil and refrigerant bled from the evaporator through a continuous still which is heated by hot gas bled from the compressor discharge line. This still scheme for separating oil is the invention of another, and

is shown simply as a typical oil recovery scheme without implication of limitation to that or any other oil recovery scheme.

The separated oil is fed to a sump maintained under suction line pressure and preferably of substantial horizontal area so that it may supply sufficient oil for all crank cases with a reduction of its own oil level not exceeding the oil level variation permissible in the crank cases. So dimensioned, the sump may be set at a height so low that, with the minimum quantity of oil, the sump oil level is little, if any, above the lowest permissible crank case oil level. The sump can be smaller and can be set higher, but at the risk that a leaky oil return valve will cause serious over feeding.

The low setting of the tank affords only a low gravity feed of oil and is practicable because strainers are used in the suction connection of the compressors with the result that the suction space on the compressor side of the strainer of a running compressor is at a lower pressure than is the suction line. No pressure equalizing connection is provided between the crank cases of different compressors, but the crank cases of all compressors are in virtually free pressure equalizing communication with their respective suction spaces. Thus in any running compressor the crank case pressure is lower than pressure in the suction line. The amount that it is lower depends on how much the particular strainer retards flow, but in any case the differential is sufficient to assure oil flow from the sump maintained at suction line pressure to the crank case of an active compressor, even when the gravity flow of oil level would be slight.

Float valves subject to oil levels in corresponding crank cases control flow of oil from the sump, each to a corresponding crank case. The floats can be in the crank cases, but I prefer to locate them in separate chambers to stabilize their action.

Where force feed lubrication is used, refinements are possible but not always required. For example, part of the oil discharged by each pump may be returned to the sump, thus assuring circulatory flow and protecting against over feeding by a leaky float valve. When this oil return scheme is used, the float valve may be contrived so as to apportion the oil drawn by the pump so that a variable part is drawn from the crank case and the remainder from the sump.

Practical embodiments of the invention will now be described by reference to the accompanying drawings, in which:

Figure 1 is a diagrammatic elevation showing three six-cylinder compressors of the so-called W-type, together with the refrigerating circuit and the oil recovery circuit.

Fig. 2 is an axial section through one of the compressors shown in Fig. 1.

Fig. 3 is a section on line 3-3 of Fig. 2.

Fig. 4 is a view similar to a portion of Fig. 1 showing a modification of the oil return connection.

Fig. 5 is a section through a type of float valve which may be substituted for those shown in Figs. 1 to 4 inclusive.

Fig. 6 is a diagram showing the simplest possible embodiment of the invention.

Fig. 7 is an axial section of the check valve and restricted bypass affording communication between the compressor suction and the crank case.

Referring first to Fig. 1, the refrigerant circuit will be traced. Three six-cylinder W-type compressors, indicated by the reference numerals C1, C2 and C3, have their suction connections in communication with a common suction line 11 and their discharge connection in communication with a common high pressure discharge line 12, through which hot compressed refrigerant flows in the gaseous phase. Most of this hot refrigerant flows through the branch 13 to condenser 14, which may be assumed to be of the water-cooled shell-and-tube type, though it may take any suitable form.

From the condenser 14 refrigerant passes by way of an expansion valve 15, here shown as a high side float valve, and liquid line 16 to an evaporator 17. This may be assumed to be of the shell-and-tube type in which the liquid to be cooled is circulated through heat exchange tubes within the shell. No effort has been made to illustrate such tubes because the particular construction of the evaporator is not a feature of the invention, nor is it novel.

From the bottom of the evaporator 17 the branch pipe 18 leads to a circulating pump 19 which delivers most of the pumped refrigerant to a spray pipe 21 within the evaporator shell 17. The sprayed refrigerant flows over the aforesaid heat exchange tubes in the evaporator. Refrigerant evaporated by heat abstracted from the tubes will pass off by way of the branch 22 to the suction line 11.

There is an oil still comprising a cylindrical shell 23 having near one end (the left-hand in this case) a partition 24. A branch from the discharge of the circulating pump 19 leads to a heat exchange coil 25 which zig-zags back and forth within the shell 23 at the right of the partition 24 and finally discharges at 26 into the space within the shell to the left of this partition. The suction line 11 is in direct communication with the top of the space to the left of partition 24 and from the bottom of this space an oil line 27 leads to the cylindrical oil sump 28. A branch of the high pressure refrigerant line 12 communicates with and delivers hot gaseous refrigerant to the interior of shell 23 to the right of the partition 24. A high side float valve 29 controls the delivery of liquefied refrigerant from this space to the evaporator 17 by way of connection 31.

Assuming that the compressors discharge compressed refrigerant, together with some oil, through the line 12, the major part of the hot gaseous refrigerant and oil passes to the condenser 14 where the refrigerant assumes the liquid phase and mixes completely with the oil.

The high side float valve 15 passes the mixture to the evaporator 17 as the liquid accumulates and since only the refrigerant evaporates in the evaporator 17, there is a tendency for oil to accumulate in the evaporator.

The pump 19 draws oil and refrigerant mixture from the evaporator, circulates part of it back to the evaporator through the sprays, but circulates a small quantity through the coil 25. At 10 the same time a limited quantity of hot gaseous refrigerant enters the shell 23 to the right of the partition 24 and delivers heat to the oil-refrigerant mixture flowing through the coil 25. The hot gaseous refrigerant is cooled and thus 15 condensed to liquid, and as it condenses is delivered by the high side float valve 29 to the evaporator. The oil-refrigerant mixture flowing through the coil 25 is heated so that when it 20 discharges at 26 under suction pressure the refrigerant evaporates and flows off to the suction line 11, while the oil drains through the pipe 27 to the oil sump 28. This still scheme, using 25 hot gas to distill refrigerant from the oil, is the invention of another and is shown here simply as a convenient and effective means for separating the oil from the refrigerant on the low pressure side of the refrigerant circuit. Other low side oil recovery schemes are known and might be used for the same purpose, it being understood that the present invention has to do with distribution of oil to the various compressors and is not limited to use with any particular system of recovery.

To assure that the oil sump 28 operates at suction line pressure, a branch of the suction line 11 is connected with the top of the sump at 32.

Each of the compressors C1, C2 and C3 is shown as of the form illustrated in Figs. 2 and 3, but the compressors may assume any form having an oil retaining crank case or oil bath. The W-type compressor is chosen for illustration 40 simply because this type usually has force feed lubrication and is being used extensively in multiple installations.

The crank case of the compressor is indicated generally at 33 and its form is clearly shown in the drawings. A double-throw crank shaft, indicated at 34, is mounted at one end in an enclosed bearing 35, and is mounted at the other 45 end in a bearing generally indicated at 36 and provided with a gas seal, not illustrated in detail because its construction is not a feature of the present invention. A grooved pulley 37 is mounted on the end of the crank shaft and serves as the means through which the compressor is driven. The usual drive involves the use of an electric motor for each compressor with multiple V-belts for which the grooved pulley 37 is intended.

Six cylinder-sleeves 38, mounted in pairs in three radiating planes with respect to the axis of the crank shaft, are fixed in a cylinder housing 39 whose form is clearly shown in Figs. 2 and 3. The housing forms a suction chamber 41 with which the suction line 11 communicates by way of the suction port 42. In this suction port is mounted a suction filter or strainer 43 which has a throttling effect whose intensity varies somewhat with the condition of the filter. The pressure differential increases if the filter becomes partially clogged.

The cylinder bushings 38 are provided with elongated side slots 44 which are inlet ports communicating with the interval between the two ends of pistons 45. These pistons are of the

hour glass type, that is to say, they have a head 46 provided with a packing ring 47, a reduced middle to which the pitman is connected, and a skirt 48 at their lower ends provided with two oil rings. The upper ring is customarily a ventilated oil ring and the lower ring is a beveled oil scraping ring. These oil rings are not packing rings so that pressure equalization occurs past them between the interior of the crank case 33 and the suction chamber 41. In addition there is a restricted port 40 which is constantly open and a ball check valve 50 which opens to permit free flow from suction chamber 41 to crank case 33. The port and check valve are associated with the fitting 60 illustrated in Fig. 7.

The inlet valves 49 are mounted in the piston head 45 and are of the annular plate type. The discharge valves 51 are of the ported disc type, are confined by a retainer 52 and are mounted in the cylinder head 53 which is bolted to the cylinder housing 39 and serves to retain the corresponding cylinder bushing 38 in place. Over each pair of side cylinder heads is a cap 54 and these communicate by passages 55 and 56 with a similar cap 57 which overlies the heads of the two vertical cylinders. Cap 57 has a discharge connection 58 leading to the high pressure line 12.

The mechanism illustrated at 59 is a relief valve for relieving excessive discharge pressure and the mechanism generally indicated at 61 is an unloader mechanism whose function is to unload partially the adjacent cylinders of a pair by opening an unloader port located at part stroke of the piston. There commonly is one of these unloaders for each pair of the four oblique cylinders of each compressor. They may be operated in any desired order by an oil pressure mechanism not shown in detail. Various other unloader mechanisms are known and may be used. The presence of the unloader is important only because it is an unfavorable factor as far as oil distribution is concerned, since it disturbs the suction pressure in the compressor. The present invention operates successfully despite the use of unloaders.

The unloader comprises a sleeve valve 62 which is urged by a spring 63 toward the unloading position shown in Fig. 3, in which position it exposes the unloader port 64. The unloader valve is closed to load the compressor by admitting oil under pressure below the piston 65 through the connection 66. The mechanism which supplies the oil under pressure to operate the piston 65 is not illustrated.

The oil sump 28 is an elongated horizontal cylinder preferably, but not necessarily, so dimensioned that when it is filled with the maximum volume of oil to the line A-B it can not overfill the crank cases of the compressors C1, C2 and C3. However, if drawn upon by all the crank cases, it will furnish sufficient oil with a fall of oil level to the line C-D to maintain a safe level of oil in all the crank cases. This eliminates, or at least minimizes, risk of over feeding which may be caused by a leaky float valve 69.

Leading from the bottom of the sump 28 is the oil supply line 67 which has three branches 68, each leading to a corresponding float valve 69. These are shown as mounted in separate housings having top and bottom connections 71 and 72 with the related crank case, but the float mechanism can be, and in commercial installations often is, mounted within the crank case.

The float is indicated at 73 and the float valve opens when the oil level is low and closes completely at the maximum desired oil level.

The oil connections just described are sufficient to assure proper oil feed, but when force feed lubrication is used certain refinements are possible. The compressor shown in Figs. 2 and 3 has beyond the bearing 35 a housing 74 which includes an oil pump of the gear type, the gears being indicated at 75 and 76 in Fig. 2. Gear 75 is driven from the end of the crank shaft 34 and drives the gear 76. The pump draws oil from the bottom of the crank case through a connection 77 and discharges it through a connection 78 to an oil filter 79, from which it passes to the oil distributing line 81 which delivers the oil to the various bearings, to the shaft seal, and to other components, according to principles well understood in the compressor art and not involved in the present invention.

A pressure regulating valve 82 is provided and conveniently is the usual loaded relief valve which returns excess oil from the pump discharge to the crank case whenever discharge pressure exceeds a set value.

With a compressor equipped as above described, it is possible to provide for the return of a part of the oil from each compressor to the sump 28, thus correcting any over feed which might occur. One way of doing so is shown in Fig. 1. From each discharge line 78 a restricted branch 83 leads to oil return line 84, which discharges into the top of sump 28.

To avoid use of a return line 84 recourse may be had to the arrangement shown in Fig. 4, in which similar parts are numbered as in Figs. 1-3 with the letter a. Here a restricted line 83a connects the pump discharge line 78a with the supply branch 68a, but the arrangement shown in Fig. 1 is considered better practice.

In any case where the connection 83 or 83a is used I may adopt a modified form of float valve shown in Fig. 5. In this figure the housing is generally indicated at 69b, the supply branch from the oil sump 28 is shown at 68b, the intake line of the oil pump is shown at 71b, and the two connections to the crank case are indicated at 71b and 72b. Thus parts including the letter b correspond to similarly numbered parts in Figs. 1 to 4 inclusive.

The housing 69b contains two chambers, a float chamber 85 and a valve chamber 86 which is at one end and occupies only part of the width of the housing 69b, as indicated. Supply connection 68b leads to a valve seat 87 at one side of chamber 86 and opposed to this is a valve seat 88 to which a connection 89 leads from near the bottom of float chamber 85.

Shiftable between the seats 87 and 88 is a double-beat poppet valve 91 which is guided by fluted end pilots extending through the valve seats. The valve 91 has collars 92 which straddle the forked head on arm 93. This arm is fast on shaft 94 which is journaled in the partition between chambers 85 and 86, and carries, fixed to it, the arm 95 of float 73b.

When oil level is low in the crank case, the pump draws oil from the sump 28. When oil level reaches the maximum desired, the pump draws exclusively from the crank case. Between these limits there is an apportioning action. This float valve causes the lubricating pumps to exert suction on the supply line, when such action is desirable, so that gravity feed flow is assisted by the pumps.

If the oil sump be kept at suction line pressure, and if the crank cases are at compressor suction pressure, and if there is sufficient throttling at the compressor intake to assure that crank case pressure for any running compressor will be slightly lower than suction line pressure, the invention can be applied provided the crank cases are isolated from one another except for connection with a common suction line. Force feed lubrication increases the problem because it increases oil discharge, but neither it nor the oil return connection 83 or 83a is essential to the invention in its broadest aspects.

To emphasize this reference is made to Fig. 6. The sump 28c has the same connections 27c and 11c as does sump 28 in Fig. 1. Compressors C4, C5 and C6 are splash lubricated and are connected to a common discharge line 12c. The refrigerating circuit and oil recovery would be the same as in Fig. 1. All crank cases are at compressor suction pressure and suction strainers or equivalent throttling means are interposed between suction line 11c and each compressor.

The parts 61c, 68c and 69c correspond to similarly numbered parts in Fig. 1 and the elevation and capacity of the sump 28c may be as described with reference to Fig. 1.

Such a system will operate successfully because protected against such rise of crank case pressure as might, if allowed to exist, cause loss of oil.

In any case where the lubricating pump returns some oil to the sump, the mounting of the sump at a low elevation is less important than in cases where there is no provision for correcting for overfeed to the crank case. Such overfeed can be caused by a leaky float valve.

When the apportioning float valve of Fig. 5 is used the maintenance of strict suction line pressure in the sump is less important than in other embodiments because the lubricating pumps exercise a definite suction feed on oil from the sump.

In the claims I shall refer to compressor intake pressure (the pressure on the compressor side of the intake filter) to differentiate from suction line pressure.

While the crank case usually retains the bath of lubricant for each compressor, the bath is the important thing and in certain claims I shall use this term to avoid any implication that the crank case necessarily retains the oil bath, other arrangements being known and occasionally used.

I claim:

1. A refrigerating circuit containing volatile refrigerant and comprising a plurality of compressors connected in parallel between a suction line and a discharge line, and a condenser, expansion valve and evaporator connected in the order stated between the discharge line and the suction line, said compressors being each of the type having a crank case subject to compressor intake pressure and containing oil for lubricating the compressor; flow retarding means interposed between the suction line and each compressor intake and serving to cause crank case pressure of any operating compressor to fall below suction line pressure as an incident to such operation; means for recovering from said circuit oil leaving the compressors with refrigerant; a sump to which said recovered oil is delivered; means connecting said sump, at a level above oil therein, with said suction line; and liquid level controlled means responsive to the

levels of oil in corresponding crank cases and controlling flow of oil from said sump to such crank case.

2. A refrigerating circuit containing a volatile refrigerant and comprising a plurality of compressors connected in parallel between a suction line and a discharge line, and a condenser, expansion valve and evaporator connected in the order stated between the discharge line and the suction line, said compressors each including a crank case subject to compressor intake pressure and containing oil, and an oil pump which draws oil from the compressor crank case and discharges it under pressure to parts of the compressor; flow retarding means interposed between the suction line and each compressor intake, serving to cause crank case pressure of any operating compressor to fall below suction line pressure as an incident to such operation; means for recovering from said circuit oil leaving the compressors with the refrigerant; a sump to which said recovered oil is delivered; means connecting said sump, at a level above the oil therein, with said suction line; liquid level controlled means responsive to levels of oil in corresponding crank cases and controlling flow of oil from the sump to each crank case; and a restricted connection from the discharge of each oil pump to said sump.

3. A refrigerating circuit containing volatile refrigerant and comprising in combination, a plurality of compressors connected in parallel between a suction line and a discharge line, and a condenser, expansion valve and evaporator connected in the order stated between the discharge line and the suction line, said compressors having crank cases containing lubricating oil, the crank cases each being subject to the intake pressure of the corresponding compressor; force feed lubricator pumps, one for each compressor; means for recovering from the circuit lubricating oil which leaves the compressors with refrigerant; a sump for collecting such oil; liquid level controlled valves, one responsive to the oil level in each crank case and controlling the supply of oil to the lubricator pump for the corresponding compressor, and serving as the crank case oil level rises and falls to vary the relative proportion of oil drawn from the crank case and from said sump; and connections for discharging a limited portion of the lubricating oil delivered by said lubricator pumps to said sump.

4. The combination of a refrigerating circuit of the compressor condenser evaporator circuit type including a plurality of compressors connected in parallel in said circuit, each compressor including lubricant bath retaining means subject to intake pressure of that compressor; means for recovering from the circuit lubricant leaving the compressors with the refrigerant; a sump for collecting such recovered lubricant; means for maintaining said sump at the suction pressure in the circuit; flow retarding means in advance of each compressor intake for causing the intake pressure of any compressor which is operating to be maintained slightly below the suction pressure of the circuit; and liquid level controlled means, one responsive to the level of the lubricant bath in each compressor and controlling the delivery of lubricant to said bath from said sump.

5. The combination defined in claim 4 in which each compressor includes a lubricating pump drawing from the lubricant bath in that compressor, and means are provided for discharging

ing a portion of the oil delivered by each such pump to said sump.

6. The combination of a refrigerating circuit of the compressor condenser evaporator circuit type containing a volatile refrigerant, the compressor thereof having a lubricant bath; means for recovering from said circuit lubricant leaving said compressor with refrigerant; a sump for collecting the recovered lubricant; a lubricating pump associated with said compressor, said pump drawing lubricant from said bath and having a restricted connection for delivering a part of the oil pumped thereby to said sump, the major portion of the remainder being returned to the bath after performing its lubricating function; and liquid level controlled means responsive to the level of lubricant in said bath and controlling the supply of lubricant from the sump to the bath.

7. The combination of a refrigerating circuit of the compressor condenser evaporator circuit type containing a volatile refrigerant, the compressor thereof having a lubricant bath; means for recovering from said circuit lubricant leaving said compressor with refrigerant; a sump for collecting the recovered lubricant; a lubricating pump associated with said compressor and having a restricted connection for delivering a part of the oil pumped thereby to said sump, the main portion of the remainder being returned to the bath after performing its lubricating function; and liquid level controlled valve means responsive to the level of lubricant in said bath and controlling the supply of lubricant to said pump, said valve means serving to connect said pump to draw lubricant in varying proportions from said sump and said bath as the lubricant level in the bath varies.

8. The combination of a refrigerating circuit of the compressor condenser evaporator circuit type containing a volatile refrigerant, the compressor thereof having a lubricant bath; means for recovering from said circuit lubricant leaving said compressor with refrigerant; a sump for collecting the recovered lubricant, said sump being subject to pressure in the low pressure side of the circuit and located at such elevation relatively to the elevation of the bath as to afford a slight gravity feed tendency from the sump to the bath, the lubricant bath being subject to compressor intake pressure; liquid level controlled means responsive to the level of lubri-

cant in said bath and controlling the supply of lubricant from the sump to the bath; and flow restricting means between the low pressure side of said circuit and the compressor intake sufficient to cause moderate depression of intake pressure below such suction pressure when the compressor is operating, whereby the tendency of flow from the sump to the bath is accentuated.

9. The combination of a refrigerating circuit 10 of the compressor condenser evaporator circuit type containing a volatile refrigerant, the compressor thereof having a lubricant bath; means for recovering from said circuit lubricant leaving said compressor with refrigerant; a sump 15 for collecting the recovered lubricant, said sump being subject to pressure in the low pressure side of the circuit and located at such elevation relatively to the elevation of the bath as to afford a slight gravity feed tendency from the sump to the bath, the lubricant bath being subject to compressor intake pressure; liquid level controlled means responsive to the level of lubricant in said bath and controlling the supply of lubricant from the sump to the bath; flow 20 restricting means between the low pressure side of said circuit and the compressor intake sufficient to cause moderate depression of intake pressure below such suction pressure when the compressor is operating, whereby the tendency of flow 25 from the sump to the bath is accentuated; and means operative when the compressor runs to deliver lubricant in limited quantity continuously from the bath to the sump.

10. The combination of a refrigerating circuit 30 inclusive of condensing means, evaporator means, and a plurality of compressors connected in parallel relationship in said circuit, each such compressor including a lubricating oil bath subject to the intake pressure of that compressor 35 and isolated from the baths of other compressors; means for collecting oil from said circuit and storing it under the pressure prevailing in the suction side of the circuit; intake flow restricting means associated with the compressor 40 intakes for causing the intake pressure of an operating compressor to fall below the pressure prevailing in said suction side; and individual valve means responsive to the level of oil in the bath of a corresponding compressor for supplying oil from said oil collecting means to respective baths to maintain the oil levels therein.

JOHN C. CONSLEY.
